UNITED STATES PATENT OFFICE.

GEORGE W. LUHREMAN, OF JERSEY CITY, NEW JERSEY, ASSIGNOR TO ANCHOR CAP & CLOSURE CORPORATION, OF BROOKLYN, NEW YORK, A CORPORATION OF NEW YORK.

METHOD AND APPARATUS FOR CONTROLLING COOLING OF PACKAGES.

Application filed January 8, 1920. Serial No. 350,239.

To all whom it may concern:

Be it known that I, GEORGE W. LUHREMAN, a citizen of the United States, residing at Jersey City, in the county of Hudson, 5 State of New Jersey, have invented certain new and useful Improvements in Methods and Apparatus for Controlling Cooling of Packages, of which the following is a specification.

10 This invention relates broadly to preserving, and pertains particularly to certain improvements in apparatus and an improved method suitable to be utilized in the processing of sealed packages with heat.

15 As is well known in the art, it is customary in the packing of various perishable commodities, such as food-stuffs, to package the material in containers, and then subject the packages thus formed to a heat treatment for

20 the purpose of cooking the material, or completing the cooking of partially cooked material, or for sterilizing the contents and packages. This processing is ordinarily carried on with apparatus in the nature of a

25 retort or autoclave in which the packages are confined for the heating treatment and retained under an induced fluid pressure for the purpose of equalizing or counteracting internal pressures induced by the processing,

30 and which would otherwise produce defective packages. In order to operate efficiently, it is necessary that the packages, at the end of the heat treatment, be cooled by means other than the ordinary radiation in

35 the atmosphere, and that such cooling operation be effected as rapidly as possible in order to permit reuse of the retort for another batch or lot of packages.

40 My present invention pertains particularly to apparatus and a method for effecting the cooling operation.

45 In the use of containers of frangible material, such as glass vessels, for packing food-stuffs, proper regulation of the cooling operation must be had in order to prevent breakage of the containers by a too sudden or too extreme change of temperature, as by application of the cooling fluid at too low a temperature.

50 One purpose of my present invention is to provide a method and apparatus whereby the cooling operation in the processing of packages in frangible containers may be

greatly expedited, may be carried on with certainty and safety, and whereby the application of cooling fluid at too great a difference in temperature from the packages may be inhibited.

55 A further object of my invention is the provision of an improved apparatus for attenuating cooling fluid during the cooling operation.

60 A further object of my invention is the provision of a method of cooling packages having frangible containers, and an apparatus for practicing the same, which method and apparatus provide for a continuous operation whereby cooling fluid at constantly decreasing temperature may be applied continuously to the packages while they are retained under an equalizing pressure.

65 Other and further objects of my invention will be obvious or pointed out hereinafter, or indicated in the accompanying claims, and in the accompanying drawings, forming a 75 part of this specification. In the drawings is illustrated a form in which an apparatus comprising my invention may be embodied, and by which the method comprising my invention may be practiced. It will be understood, however, that my improved method is not limited in its practice to any particular form of apparatus, and that the form, arrangement and details of the device illustrated may be varied without departing from 80 the spirit of my invention or the scope of the appended claims in which it is defined.

75 In the accompanying drawings, Figure 1 represents a diagrammatic illustration of a processing retort in sectional elevation, together with certain appertinent apparatus including an illustrative form of my invention, shown partly in section.

85 Figure 2 illustrates a modified and simplified form of device in which my invention 90 may be embodied, and by which my improved method may be practiced.

95 Described generally, the method constituting my invention comprises the modifying of a cooling fluid with heat so as to attenuate the fluid to form a cooling medium, and applying the cooling medium in the 100 form of a moving body or column of liquid, to the articles to be cooled, meanwhile graduating the temperature of the cooling medium 105 supplied, so that it is progressively cooler

and is effective to displace the preceding warmer cooling medium from about the articles.

Described generally, an apparatus embodying my invention includes a retort or pressure sustaining receptacle in which the packages are processed, together with means for commingling heating and cooling fluids before introduction into the retort, and including means for regulating the supply of said fluids independently, together with an arrangement for supplying the cooling medium into the retort and withdrawing it from the retort in such fashion as to produce a continuous flow of the cooling medium of gradually decreasing temperature about the packages therein.

The invention may be more specifically understood by reference to the accompanying drawings in which the reference character 1 is applied to designate a retort, which may be of any suitable form for the reception of the intended packages, said retort being closed by a suitable closure 2, here represented in the form of a door. The retort is adapted for the reception of packages C which may be placed and sustained in the retort in any suitable fashion, as by means of the charging basket 4. It is contemplated that the retort shall be properly equipped to accomplish the intended treatment of the packages therein with heat for the desired purpose. This may be effected through any suitable means, 5, by way of which the proper equalizing pressure also may be maintained within the retort.

From a source of supply of a suitable cooling medium, such as cold water, a conduit 6 leads to a modifying device 7, to which device leads also a connection 8 from a source of heat supply. In the particular embodiment herein shown, connection 8 is in the form of a steam pipe such as would be effective to conduct steam from a suitable boiler. The feed of cooling fluid to the device 7 is controlled by suitable means 9, and the supply of heat to the device 7 is controlled by suitable means 10. In the present embodiment the modifying device 7 is in the nature of a suction connection wherein the steam under pressure and the water under pressure are brought into contact so that there will be an exchange of heat between them to raise the temperature of the water to the desired point. Through the proper operation of the controlling means 9 and 10, the necessary control is exercised upon the cooling fluid and the heat to produce a cooling medium of the desired temperature. In communication with the modifying device 7 is an inlet pipe 11 by which the cooling medium may be conducted into the retort, and a discharge pipe 12 by which the cooling medium may be conducted to another point of disposal. Suitable means

14 is provided for the control of these conduits. A thermically operated device 13, including the indicator 15, is disposed in the connection through which the cooling medium is conducted from the modifying device 7. The arrangement as thus organized constitutes an attemperating apparatus whereby the temperature of the cooling fluid may be raised to a degree which may be applied with safety to the frangible containers of hot packages in the retort. In accomplishing this the means 14 is first set so that communication through the inlet pipe 11 is closed, and communication through the discharge pipe 12 is opened. By suitable adjustment of the controlling devices 9 and 10 a supply of heat and of cooling fluid in proper proportion is secured, the mixture being allowed to discharge through the pipe 12 until the proper temperature is shown in the indicator 15. Upon the proper temperature being reached, as ascertained from the indicator 15, the means 14 is set to open communication through the inlet pipe 11 and close communication through the discharge pipe 12, thereby introducing the cooling medium into the retort.

In order to secure a thorough and uniform commingling of a heating fluid such as steam with a cooling fluid such as water, to produce the desired cooling medium, it may be desirable to insert a mixing device 17 into the attemperating apparatus. This mixing device may be incorporated as a part of the modifying device 7. In the embodiment illustrated I have shown it associated with the modifying device in such relationship that the steam and water discharged from the device 7 are thrown first upon a baffle 18 which is in the form of a cone and which diffuses the fluids and deflects them against the reentrant conical or funnel shaped baffle 19. From the smaller or discharge end of this baffle the fluids are discharged onto a second conical baffle 20 and by it diffused on to another reentrant baffle 21. The mixer may be equipped with as many of these baffle arrangements as may be desired. The result of the passage of the fluids through this device is to bring the heating and cooling fluids into more intimate contact so that they are more uniformly and thoroughly commingled before introduction into the retort. It is obvious that other forms of mixing apparatus may be employed, the essential feature thereof being the capacity of the device for a continuous operation so that the proper attemperating of the cooling fluid may be carried on during its movement to the retort. Moreover, the thermically operated device 13 may be arranged to exercise an automatic control upon the attemperating operation. This may be accomplished by means of apparatus in the nature of a motor valve 22 arranged

to control either or both the heat and the cooling fluid so that the supply of the two may be held in proper proportions always to maintain the desired temperature of the 5 cooling medium. Such thermically operated motor valves are well known in the art, and are arranged so that they may be set to operate between predetermined maximum and minimum temperature limits. The device 22 being set for the predetermined maximum and minimum temperatures, any variation of the cooling medium at the device 13 outside of this predetermined range will occasion an operation of the device 22 10 to properly adjust the proportion of heating and cooling fluids to restore the desired temperature. The cooling medium introduced into the retort from the apparatus above described is conducted away from the 15 retort by means of an outlet pipe 24. This pipe is controlled by a suitable flow regulating means 25 so that the rate of discharge from the retort may be suitably regulated and varied.

25 In the carrying out the cooling process by means of the apparatus above described, it will be understood that the proper temperature of the cooling medium for the initial application to the heated packages having 20 been obtained by the proper adjustment of the means 9 and 10, such cooling medium is introduced into the retort through the pipe 11, where it comes into contact with the packages, absorbing heat from them and thereby reducing their temperatures. The 25 retort may be entirely filled with the cooling medium introduced at the initial temperature, if desired, and said charge of the cooling medium permitted to remain therein for a sufficient time to permit the desired 30 exchange of heat between the hot packages and the cooling medium; or the temperature of the cooling medium may be reduced at intervals by suitable adjustment of the means 35 9 and 10 before the retort is entirely filled with fluid introduced at the initial temperature, so that a continuous flow of cooling medium may be maintained, and the packages in the retort subjected to the influence 40 of successive zones or quantities thereof at progressively lower temperatures. In the event the first procedure specified is followed, upon the initial charge of cooling medium having been allowed to remain in 45 the retort for the desired length of time, it then may be gradually displaced by the introduction of another charge of cooling medium at lower temperature, and this procedure repeated until the packages have been 50 cooled to the desired degree. The desired variation in temperature of the cooling medium may be attained periodically by adjustment of the means 9 and 10; and in the 55 event the automatic temperature control means 13 and 22 are employed, by the pe-

riodic resetting of the temperature range of the latter. The flow control device 25 may be susceptible of suitable operation to maintain the desired degree of fluid pressure upon the packages within the retort during 70 the cooling operation, and to regulate the rate of discharge of cooling medium from the retort.

Employment of the method of cooling above described permits the necessary reduction in temperature of the packages in a minimum time with entire safety to the frangible containers, and requires the employment of a minimum quantity of cooling 75 medium.

The application of the cooling medium to the packages is made in such fashion that the portions of the fluid having different temperatures are allowed to remain always in their natural physical relationship so that 80 there is not such a commingling of the entering cooling medium and warmer fluid within the retort as would tend to lower the cooling efficacy of the former. This method takes advantage of the physical phenomenon 85 that heat exchange is most rapidly accomplished between matter having the greatest difference in temperature, and insures the application of the coldest cooling fluid to the coolest packages before such cooling 90 medium has been subjected to the heat influence of the warmer fluid within the retort. Owing to the fact that the space within the retort is so largely occupied by the packages either when they are stacked therein, or 95 when they are disposed in a charging cage, there will be no direct path or channel of flow between the inlet and outlet such as would tend to produce side eddies or mixing 100 of the successively applied zones or strata 105 of cooling medium. This method, therefore, accomplishes a progressive cooling of the packages while maintaining the greatest practicable difference in temperature between them and the cooling medium. Said 110 cooling of the packages is progressive not only as to each particular package, but also as to the charge or lot of packages within the retort, due to the increasing temperature of cooling medium in the different 115 zones from the inlet to the discharge.

By virtue of the apparatus above described my method may be put in practice economically and efficiently both as to cost of installation of the apparatus itself, and 120 as to cost of operation thereof. The apparatus is designed with the idea of making it as simple as possible so that it may be operated with certainty without requiring a high degree of skill or term of experience. 125

Having thus described my invention, what I claim is:

1. The method of cooling sealed packages having frangible containers, which includes maintaining the packages under an equaliz- 130

- ing pressure, supplying a cooling fluid, at-temperating the cooling fluid with reference to the temperature of the packages to provide a cooling medium, applying successive 5 quantities of the cooling medium at successively reduced temperatures to packages disposed in successive zones, and withdrawing the cooling medium from the zone of highest temperature.
- 10 2. The method of cooling packages, which includes supplying a cooling fluid, attemperating the cooling fluid with reference to the temperature of the packages to provide a cooling medium, successively applying to 15 the packages quantities of the cooling medium arranged in strata of progressively lower temperatures and withdrawing the cooling medium from the stratum of highest temperature.
- 20 3. The process of cooling sealed packages comprising attemperating a cooling fluid with reference to the temperature of the packages to provide quantities of a cooling medium successively at lower temperatures, 25 moving said quantities of cooling medium successively onto the packages so that each of said quantities is effective to displace preceding quantities in the direction of movement of the cooling medium, withdrawing 30 the cooling medium after it has moved beyond the packages, and maintaining the packages meanwhile under an equalizing pressure.
4. The method of cooling packages, comprising disposing the packages in a group, commingling a heating fluid and a cooling fluid to produce a cooling medium, applying said cooling medium continuously to the packages in quantities arranged in strata of 35 progressively lower temperatures by displacing preceding quantities with succeeding quantities, and withdrawing the cooling medium after its movement across the group of packages.
- 40 5. The process of cooling packages comprising maintaining a group of packages within a receptacle, commingling a heating fluid and a cooling fluid exterior of the receptacle to provide a cooling medium, introducing quantities of said cooling medium 45 into the lower portion of the receptacle 50 forming temperature zones in said receptacle at progressively reduced temperatures, occasioning by said introduction of cooling medium displacement of preceding quantities by succeeding quantities and the movement of the cooling medium across the group of packages, whereby the packages in said group are subjected to successive zones of progressively lower temperatures, and withdraw- 55 ing the cooling medium from the upper portion of the receptacle.
6. In a preserving apparatus, the combination of a retort for the reception of packages, cooling agent supply means, heat- 60 ing agent supply means, an attemperating apparatus operable continuously to associate a cooling agent and a heating agent from said supply means to provide a cooling medium, a discharge pipe affording an outlet for fluid 65 from the attemperating apparatus to thereby permit a precise regulation on the temperature of the cooling medium prior to its entrance to the retort, a thermal indicating device responsive to changes in temperature of the 70 cooling medium so provided, means for conducting cooling medium from said attemperating apparatus into the retort at the lower portion thereof, and means permitting the continuous withdrawal of cooling 75 medium from said retort at the upper portion thereof.
7. In an apparatus for preserving, the combination of a retort for the reception of packages, steam supply means, water supply 80 means, an attemperating device for commingling steam and water from said supply means to produce a cooling medium, means for regulating the supply of steam and water respectively, a thermically operated de- 85 vice for indicating the temperature of the cooling medium, a discharge pipe affording an outlet for fluid from the attemperating device independent of said retort, an inlet pipe for conducting cooling medium from 90 the attemperating device into the lower portion of the retort, means for controlling flow from the attemperating device through said pipes respectively, and means for conducting 95 fluid from the upper portion of the retort. 100

GEORGE W. LUHRMANN.
